(57) **CLAIM**

The ornamental design for a security sticker for delivered food containers, as shown and described.

DESCRIPTION

FIG. 1 is a perspective view of a security sticker for delivered food containers shown in use as applied to a pizza box, showing my new design.

FIG. 2 is a front view of the security sticker for delivered food containers;

FIG. 3 is a left side view thereof with a right side view, a top view, and a bottom view being a mirror image;

FIG. 4 is an exploded front view of the security sticker for delivered food containers; and,

FIG. 5 is an exploded rear view thereof.

The broken line showing of a portion of a pizza box in FIG. 1 and the word TOPPINGS in FIGS. 1, 2 and 4 are for the purpose of illustrating environment and forms no part of the claimed design.
